UNITED STATES PATENT OFFICE.

AAREIEL E. GOODLOE, OF CHATTANOOGA, TENNESSEE.

SURGICAL INSTRUMENT.

1,397,732.

Specification of Letters Patent.

Patented Nov. 22, 1921.

Application filed April 13, 1920. Serial No. 373,520.

To all whom it may concern:

Be it known that I, AAREIEL E. GOODLOE, a citizen of the United States of America, residing at Chattanooga, in the county of 5 Hamilton and State of Tennessee, have invented certain new and useful Improvements in Surgical Instruments, of which the following is a specification.

This invention relates to certain new and 10 useful improvements in surgical instruments of that class designed for insertion into the natural passages, organs and cavities of the human or animal body for inspection and for the removal of foreign matter and bodies 15 and for the treatment of the body or other similar surgical operations.

The chief improvement consists in combining a tube or barrel for the ordinary uses for which instruments of this class are used, 20 with a jaw or blade at the outer extremity of the tube so constructed that the jaw and tube combine to grasp certain objects and at the same time vision of the object is maintained. The same principle is involved 25 when, by adding certain and special knives at the outer or tip end of the tube, certain surgical operations may be performed, and tissue can be held so as to be inspected, diseased tissue and tumors or other growths 30 can be removed for examination and other purposes.

While the improvements forming the subject matter of my invention may be applied to any tube of suitable size and shape for 35 the insertion of the same into passages, etc., of the human body, and for the removal of bodies, etc., from any cavity, opening or passage of the human or animal body for the purposes stated, the invention will be described in connection with a bronchoscope, 40 designed to facilitate inspection and particularly the removal of foreign bodies from the human bronchi, as the instrument is illustrated in the accompanying drawing, in 45 which—

Figure 1 is a side elevational view of a bronchoscope constructed in accordance with the present invention and with its parts in their normal position, the handle being 50 partly broken away,

Fig. 2 is a substantially central longitudinal sectional view of the device shown in

Fig. 1, parts being broken away and parts being removed,

Fig. 3 is a top plan view of the device 55 shown in Fig. 1,

Fig. 4 is a transverse sectional view taken substantially upon line IV—IV of Fig. 1,

Fig. 5 is a plan view of the jaw carrying strip,

Fig. 6 is an elevational view of the outer end portion of the device shown in Fig. 1 with the jaw raised or in the first step of its movement,

Fig. 7 is a view similar to Fig. 6 with the 65 jaw and associated members in the second step of their movement.

Fig. 8 is a view similar to Fig. 7 with the jaw in its third step of movement or first position in closing, and

Fig. 9 is a longitudinal sectional view of the outer end portion of the bronchoscope with a modified form of carrying member 70 for the jaw.

The four positions of the jaw disclosed in 75 Figs. 1, 6, 7 and 8 are represented for convenience of description by showing the four stages of opening and closing of the jaw.

Like reference characters indicate corresponding parts throughout the several 80 views.

Referring more in detail to the several views, the present invention includes a long tube or barrel 5 which is open at both ends and has a suitable handle 6 rigidly fastened 85 on one end thereof so that clear vision may be had through the tube at all times. A sheet metal strip 7 of the form more clearly shown in Fig. 5 is slidably disposed upon the upper portion of the barrel 5, and this 90 strip 7 is arch-shaped in cross section as clearly shown in Fig. 4, while the forward end of said strip is forked and apertured to provide a pair of ears 8 to which the jaw 9 is hinged adjacent the inclined forward end 95 of the barrel 5. The rear end of the strip 7 is slidably extended through a slot in the handle 6, and at set screw 10 is threaded into the handle 6 so that its inner end bears upon the upper face of the adjacent portion 100 of the strip 7. The office of the screw 10 is to adjustably resist movement of the strip 7 longitudinally relative to the barrel 5 as will presently become apparent, and said

strip 7 is provided with a head 11 upon its inner end so as to prevent the strip from moving forwardly through and out of the slot in the handle 6. The barrel 5 is provided with a suitable shield 12 within which the forward portion of the strip 7 slides so that contact of the strip 7 with the walls of the passage of the human body is prevented.

A rod 13 is slidably disposed within a longitudinal groove 14 provided in the upper portion of the barrel 5 beneath the strip 7, and this rod 13 is pivotally connected at its forward end to the jaw 9 as at 15 and has its inner end bent upwardly so as to 10 freely extend through the longitudinal elongated slot 16 provided in the jaw carrying strip 7, and to extend through a perforation in the finger piece or slide 17 which is mounted upon the barrel 5 adjacent the handle 6 whereby, when said slide or finger piece is moved longitudinally of the barrel 5, similar movement is imparted to the rod 13. When the finger piece 17 is moved 15 forwardly, the controlling rod 13 is caused to move forward so as to swing the jaw 9 upwardly from the position of Fig. 1 to the position of Fig. 6, and if the finger piece is moved still farther forwardly, the strip 7 is caused to slide forwardly upon the barrel 20 so as to extend the jaw outwardly some distance beyond the outer end of said barrel 5 as shown in Fig. 7. The closing of the jaw is accomplished by the same principle or general operation but the order of movement is reversed. In other words, for closing the jaw, the finger piece 17 is moved inwardly or rearwardly upon the barrel 5 so as to cause a pull upon the controlling rod 13 and lower the jaw to the position of 25 Fig. 8. When this takes place, the angular rear inner end of the rod 13 engages the inner end wall of the slot 16 of the strip 7 and causes the latter to slide rearwardly until the jaw is returned to its normal position as shown in Fig. 1. The controlling rod 13 always moves forwardly or backwardly before the sliding piece or strip 7 moves, due to the friction on said controlling rod 13 being less than that on the sliding 30 piece or strip 7. This greater friction upon the strip is illustrated as obtained by means of the screw 10, but other means may be utilized, or such friction may be obtained by placing the thumb or finger on strip 7. 35 The finger piece 17, includes a tubular body having finger receiving rings 18 rigidly connected thereto and extending upwardly and downwardly therefrom. The body of the finger piece 17 is provided with an enlargement 19 on its underside through which extends a radial slot 20, having a locking slide 21 disposed to slide upwardly and downwardly therein for engaging the roughened upper surface 22 with the under surface 40 of a strip 23, or for disengaging said face

from the strip 23 as desired, the strip 23 being soldered or otherwise fastened at the under side of the barrel 5 within the finger piece 17 to the tube 24. The tube 24 is rigidly fastened to the under side of the barrel 5 and opens at its distal end into the tube 5, alongside and adjacent to the aperture 32 of the drainage tube 31. The relative position of the light and the distal opening of drainage tube is shown in Fig. 2 at 45 32 and 25, the perforation 32 being adjacent light 25 for securing perfect drainage of region adjacent or near the light. Thus as will be seen, the upper and lateral surface of light globe is adjacent to the opening of drainage tube and the light rays emanate from the bottom of the distal end of tube 5.

The light is utilized for the purpose of illuminating the interior of tube and passage in which the instrument is used, and the wires from the lamp 25 which are broadly shown in Fig. 1 at 26, are extended rearwardly through the tube 24 to a suitable source of electricity. This source of electricity may reside in the ordinary form of dry cell battery which may be carried in the pocket of the operator and flexibly connected to the bronchoscope.

The locking slide 21 is of such length as 50 to extend below the enlargement 19 of the finger piece 17 and is provided in its lower end with a transverse inclined elongated slot 27 into which extends the laterally extending pin 28 which is rigidly carried by a finger operated lever 29, the lever 29 being pivoted as at 30 to the finger piece 17 so as to be swung forwardly or rearwardly as desired. As the slot 27 is inclined downwardly, and rearwardly it will be seen that 55 when the lever 29 is pressed rearwardly, the slide 21 is caused to rise until its face 22 engages the strip 23, and the finger piece 17 is thereby effectively held against movement on and relative to the barrel 5 so that the jaw 9 is effectively held and maintained in any of its positions when found necessary. By this means, the operator is enabled to obtain a strong grasp on any object which may be within the grasp of the jaw 9. 60

It is somewhat usual in the present class of devices to place a drainage tube at the top of the barrel 5, and this is quite impractical with the present construction and somewhat undesirable. I place this drainage 65 tube alongside of the tube 24 as shown at 31 and thereby make use of the space formed by the joining of the tube 24 to the barrel 5. The drainage tube communicates at its forward end with the interior of the barrel 5 by means of a perforation 32 provided in the latter at its forward end, and adjacent to the upper surface of the light bulb 25, both drainage tube 31 and light carrying tube 24 opening adjacent and within the 70

forward end of barrel 5. The drainage tube extends rearwardly alongside of the tube 24 to a point adjacent the handle 6 where its inner end may extend upwardly into any 5 convenient position as at 33.

The operation of the jaw 9 in the manner illustrated in Figs. 1, 6, 7, and 8 may be obtained by other means than by the use of strip 7, and an illustration of a modification 10 to secure this is found in Fig. 9 wherein the jaw 9 is hinged to a cuff or sleeve 34 which is slidable longitudinally upon the forward end of the barrel 5 and has a set screw 35 threaded therethrough so as to engage the 15 barrel 5 and offer frictional resistance to the sliding movement of the sleeve 34. It is to be understood that the construction of the bronchoscope will be substantially identical in Fig. 9 as in the other figures with the 20 exception that the strip 7 is eliminated and the sleeve 34 is substituted in its place.

It will be understood that the jaw 9 may be given simple opening and closing swinging movements from the position of Fig. 1 25 to the position of Fig. 6 and then back to the position of Fig. 1 by threading the set screw 10 into firm engagement with the strip 7 or the set screw 35 with the barrel 5 when found desirable.

From the foregoing description it is believed that the construction and operation 30 as well as the advantages of the present invention will be readily understood and appreciated by those skilled in the art.

It is of course to be understood that minor 35 changes may be made in the form, combination and arrangement of the various parts herein specifically set forth without departing from the spirit and scope of the invention as claimed.

What I claim as new is:—

1. In a surgical instrument of the class described, a barrel having a handle upon its inner end, a finger piece slidable upon said 45 barrel within reach of the fingers of a person's hand gripping said handle, a jaw at the outer end of said barrel and coöperating with the latter to grasp objects, a friction controlled sliding piece carried by the barrel and having said jaw hinged thereto, and a 50 controlling rod for swinging said jaw connected to said finger piece whereby, when the finger piece is slid forwardly the jaw is caused to first swing upwardly and then move forwardly relative to the barrel.

2. In a surgical instrument of the class described, a barrel having a handle upon its inner end, a finger piece slidable upon said barrel within reach of the fingers of a person's hand gripping said handle, a jaw at the outer end of said barrel and coöperating 60 with the latter to grasp objects, a friction controlled sliding piece carried by the barrel and having said jaw hinged thereto, 65 a controlling rod for swinging said jaw

connected to said finger piece whereby, when the finger piece is slid forwardly the jaw is caused to first swing upwardly and then move forwardly relative to the barrel, and finger operated means carried by said finger piece for locking the latter against movement relative to said barrel.

3. In a surgical instrument of the class described, a barrel having a handle upon its inner end, a finger piece slidable upon said barrel within reach of the fingers of a person's hand gripping said handle, a jaw at the outer end of said barrel and coöperating with the latter to grasp objects, a friction controlled sliding piece carried by the barrel and having said jaw hinged thereto, a controlling rod for swinging said jaw connected to said finger piece whereby, when the finger piece is slid forwardly the jaw is caused to first swing upwardly and then move forwardly relative to the barrel, a light carrying tube secured to the under side of said barrel, and a drainage tube extending longitudinally of the barrel along side of said light carrying tube.

4. A surgical instrument of the class described comprising a barrel, a jaw at the forward end of said barrel, a sliding piece movable longitudinally of the barrel and having said jaw hinged thereto, a controlling rod pivoted to said jaw, a finger piece slidable upon the barrel and attached to said controlling rod, and means bearing upon said sliding piece adapted to resist movement of the latter under adjustable degrees of friction whereby, when the finger piece is moved relative to the barrel, the jaw may be swung upwardly and downwardly to open and closed positions or may be swung upwardly and then moved forwardly of the 95 barrel as desired.

5. A surgical instrument of the class described comprising a barrel, a jaw hinged at the forward end of said barrel, a sliding finger piece upon the barrel, and means operatively connecting said finger piece with said jaw whereby the latter is automatically caused to first swing upwardly and then move forwardly relative to the barrel upon forward movement of said finger piece 110 and whereby said jaw is caused to first swing downwardly and then move rearwardly against the adjacent end of the barrel when said finger piece is subsequently moved rearwardly of the barrel.

6. A surgical instrument of the class described comprising a barrel, a jaw hinged at the forward end of said barrel, a sliding finger piece upon the barrel, means operatively connecting said finger piece with said 115 jaw whereby the latter is automatically caused to first swing upwardly and then move forwardly relative to the barrel upon forward movement of said finger piece and whereby said jaw is caused to first swing 120

- downwardly, and then move rearwardly against the adjacent end of the barrel when said finger piece is subsequently moved rearwardly of the barrel, and an upright handle rigidly mounted upon the inner end of said barrel adjacent said finger piece. 7. A surgical instrument of the class described comprising a barrel, a jaw hinged at the forward end of said barrel, a sliding finger piece upon the barrel, means operatively connecting said finger piece with said jaw whereby the latter is automatically caused to first swing upwardly and then move forwardly relative to the barrel upon forward movement of said finger piece, and whereby said jaw is caused to first swing downwardly and then move rearwardly against the adjacent end of the barrel when said finger piece is subsequently moved rearwardly of the barrel, and means carried by said finger piece operable at will to hold the latter against movement relative to the barrel. 8. A surgical instrument of the class described comprising a barrel having an elongated strip slidably mounted thereon, a jaw at the forward end of said barrel hinged to the forward end of said strip, a handle carried by the inner end of said barrel and having a slot through which said strip extends, means carried by the handle for adjustably frictionally engaging said strip, a finger piece slidable upon the barrel adjacent said handle, said strip having an elongated slot therethrough, a controlling rod arranged beneath said strip and slidably longitudinally of the barrel, said controlling rod having its outer end pivoted to said jaw for swinging the latter forwardly and downwardly and having its inner end rigidly attached to said finger piece and loosely projecting through the elongated slot of said strip. 9. A surgical instrument of the class described comprising a barrel having an elongated strip slidably mounted thereon, a jaw at the forward end of said barrel hinged to the forward end of said strip, a handle carried by the inner end of said barrel and having a slot through which said strip extends, means carried by the handle for adjustably frictionally engaging said strip, a finger piece slidable upon the barrel adjacent said handle, said strip having an elongated slot therethrough, a controlling rod arranged beneath said strip and slidably longitudinally of the barrel, said controlling rod having its outer end pivoted to said jaw for swinging the latter forwardly and downwardly and having its inner end rigidly attached to said finger piece and loosely projecting through the elongated slot of said strip, a vertically movable locking slide carried by said finger piece, and manually operable means for moving said slide to retain the finger piece against movement on the barrel. 10. In a surgical instrument of the class described, an open ended vision barrel, a jaw hinged at one end of the barrel and co-operating with said end of the barrel to grasp objects, said jaw having an opening co-operating with the bore of the barrel whereby vision of the objects is maintained, and means to swing said jaw rearwardly toward or forwardly away from said end of the barrel. 11. In a surgical instrument of the class described, an open ended vision barrel, a jaw hinged at one end of the barrel and co-operating with said end of the barrel to grasp objects, and means to swing said jaw rearwardly toward or forwardly away from said end of the barrel. 12. In a surgical instrument of the class described, an open ended vision barrel, a jaw movably mounted at one end of the barrel and co-operating with said end of the barrel to grasp objects, and means to move said jaw rearwardly toward or forwardly away from said end of the barrel. 13. In a surgical instrument of the class described, a vision barrel having means at its forward end to assist in performing a surgical operation, a light bulb carrying tube secured to the under side of said barrel, and a drainage tube extending longitudinally of the barrel and adjacent to the light bulb carrying tube. 14. In a surgical instrument of the class described, a vision barrel having means at its forward end to assist in performing a surgical operation, a light bulb carrying tube secured to the under side of said barrel, and a drainage tube extending longitudinally of the barrel and adjacent to the light bulb carrying tube, the drainage tube entering the barrel at its forward end adjacent the surface of the light bulb. 15. In a surgical instrument of the class described, an open ended vision barrel, a member for assisting in performing a surgical operation hinged at one end of the barrel and co-operating with said end of the barrel to grasp objects, and means to swing said member rearwardly toward or forwardly away from said end of the barrel. 16. In a surgical instrument of the class described, an open ended vision barrel, a member for assisting in performing a surgical operation hinged at one end of the barrel, means to swing said member rearwardly toward or forwardly away from said end of the barrel, and means to move said member bodily rearwardly toward or forwardly away from said end of the barrel independently of the swinging movement of said member. 17. In a surgical instrument of the class

described, an open ended vision barrel, a member for assisting in performing a surgical operation hinged at one end of the barrel, means to swing said member rearwardly toward or forwardly away from said end of the barrel, means to move said member bodily rearwardly toward or forwardly away from said end of the barrel independ-

ently of the swinging movement of said member, and manually operable means to releasably hold said member at any desired angle to which the same may be swung relative to the longitudinal axis of said barrel.

In testimony whereof I affix my signature.

AAREIEL E. GOODLOE.
